(57) **CLAIM**

The ornamental design for a blade sharpening assembly, as shown and described.

DESCRIPTION

FIG. 1 is a top, front, right side perspective view of a blade sharpening assembly attached to a blade sharpening clamp system showing my new design;

FIG. 2 is a top, front, right side perspective view of the blade sharpening assembly;

FIG. 3 is an exploded top, front, right side perspective view thereof;

FIG. 4 is a bottom, rear, left side perspective view thereof;

FIG. 5 is an exploded bottom, rear, left side perspective view thereof;

FIG. 6 is a front elevational view thereof;

FIG. 7 is an exploded front elevational view thereof;

FIG. 8 is a rear elevational view thereof;

FIG. 9 is an exploded rear elevational view thereof;

FIG. 10 is a right side elevational view thereof, the left side being a mirror image;

FIG. 11 is an exploded right side elevational view thereof, the left side being a mirror image;

FIG. 12 is a top plan view thereof; and,

FIG. 13 is a bottom plan view thereof.

The broken line showing of the blade sharpening clamp system in FIG. 1 is provided for purposes of environment and forms no part of the claimed design.
